UNITED STATES PATENT OFFICE.

ETHEL CHANTLAND, OF CHICAGO, ILLINOIS.

DESIGN FOR A PILLOW TOP.

Application filed February 10, 1926. Serial No. 16,469. Term of patent 7 years.

To all whom it may concern:

Be it known that I, ETHEL CHANTLAND, a citizen of the United States, residing at Chicago, in the county of Cook and State of Illinois, have invented a new, original, and ornamental Design for Pillow Tops, of which the following is a specification, reference being had to the accompanying drawing, forming part thereof.

The figure is the face view of a pillow top, showing my new design.

I claim:

The ornamental design for a pillow top, as shown.

ETHEL CHANTLAND
